UNITED STATES PATENT OFFICE.

DODSON HASLUP, OF GRAFTON, WEST VIRGINIA.

CAP-REMOVER.

1,294,658.

Specification of Letters Patent. Patented Feb. 18, 1919.

Application filed December 19, 1918. Serial No. 267,492.

To all whom it may concern:

Be it known that I, DODSON HASLUP, a citizen of the United States, residing at Grafton, in the county of Taylor and State of West Virginia, have invented a new and useful Cap-Remover, of which the following is a specification.

It is the object of this invention to provide a simple device for puncturing and removing milk bottle caps, the structure being capable of being manufactured cheaply out of sheet metal, and being so constructed that it may be grasped readily between the thumb and fore finger of the operator.

15 It is within the province of the disclosure to improve generally and to enhance the utility of devices of that type to which the invention appertains.

With the above and other objects in view, 20 which will appear as the description proceeds, the invention resides in the combination and arrangement of parts and in the details of construction hereinafter described and claimed, it being understood that, within 25 in the scope of what is claimed, changes in the precise embodiment of the invention shown can be made without departing from the spirit of the invention.

In the accompanying drawings:—

30 Figure 1 shows in side elevation, a device constructed in accordance with the invention, in place on the cap of a milk bottle; Fig. 2 is a side elevation wherein the structure is viewed at right angles to the showing of Fig. 35 1; and Fig. 3 is a bottom plan.

The device forming the subject matter of this application preferably is fashioned from a single piece of metal and includes a base 1 provided along one edge with an upstanding back 2 which may be in the form of an elliptical disk supplied at one edge with a spur 3. The base 1 is provided along its opposite edge with an upstanding flange 4, disposed at an obtuse angle to the base and terminating in a tongue 5, located at an obtuse angle to the flange, the tongue 5 slanting inwardly toward the back 2, both in the direction of the length of the tongue and in the direction of the width of the tongue, as designated by the

reference numeral 6. A prong is struck from 50 the flange 4 and from the base 1, the prong, denoted by the numeral 7, projecting outwardly beyond the flange 4. The prong 7 defines an acute angle with the base 1, as indicated at 8 and is reversely curved as shown 55 at 9.

In practical operation, a hole may be made 60 in a milk bottle cap 15, by means of the spur 3, and into this hole, the prong 7 may be thrust, the reverse curvature of the prong, 65 indicated at 9, facilitating the entrance of the prong into the opening in the cap 15. The prong 7 may be inserted readily 70 into the opening in the cap, since the prong projects laterally beyond the flange 75 4, as shown in Fig. 1. Because the prong 7 forms an acute angle, at 8, with the base 1, the cap 15 will be wedged and held securely between the prong and the base. The back 2, being of elliptical disk-like form, is adapted to receive the thumb of the operator, the forefinger supported on the tongue 5, and because the tongue 5 slants inwardly, in the direction of its width, and in the direction of its length, toward the back 75 2, the forefinger finds a convenient support on the tongue, when the device is grasped between the thumb and the forefinger as indicated in Fig. 1.

Having thus described the invention, what 80 is claimed is:—

A device of the class described, fashioned from a single sheet of metal and including a base provided along one edge with an upstanding back, and provided along its opposite edge with an upstanding flange terminating in a tongue which slants inwardly toward the back, there being a prong struck from the flange and the base, the prong defining an acute angle with the base, and being 85 extended laterally beyond the flange. 90

In testimony that I claim the foregoing as my own, I have hereto affixed my signature in the presence of two witnesses.

DODSON HASLUP.
